COMPARTMENTED TRAY OR THE LIKE

Marten Gottsegen, 2801 N. Sheridan Road, Chicago, Ill.

Filed Jan. 16, 1962, Ser. No. 68,329

Term of patent 7 years

(Cl. D44—10)

FIG. 1

FIG. 2

FIG. 1 is a top plan view of a compartmented tray or the like embodying my new design;

FIG. 2 is a bottom view thereof;

FIG. 3 is a side elevational view thereof;

FIG. 4 is a similar view from the opposite side thereof;

FIG. 5 is an end elevational view thereof;

FIG. 6 is a similar view from the opposite end thereof;

FIG. 7 is a sectional view taken substantially on the plane of irregular line 7—7 in FIG. 1 and viewed in the direction indicated; and

FIG. 8 is a sectional view taken on the plane of line 8—8 in FIG. 1 and viewed in the direction indicated.

I claim:

The ornamental design for a compartmented tray or the like substantially as shown.
